CLAIM

I claim the ornamental design for a panel tread for a paving system, as shown and described.

DESCRIPTION

FIG. 1 is a top perspective view of a panel tread for a paving system, showing my new design;

FIG. 2 is a bottom perspective view thereof;

FIG. 3 is a top plan view thereof;

FIG. 4 is a bottom plan view thereof;

FIG. 5 is a right side elevational view thereof, the left side elevational view being a mirror image thereof; and,

FIG. 6 is a front end elevational view thereof, the rear end elevational view being a mirror image thereof.
